KOM, OF PLEASANTVILLE, NEW JERSEY

RAILWAY-RAIL ANCHOR

Application filed July 3, 1929. Serial No. 375,856.

This invention relates to new and novel improvements in rail anchors formed from a single piece of metal especially designed to be fixedly secured to the base portion of a 5 railway track rail, and in engagement with stationary parts of the railway road bed for the purpose of preventing longitudinal displacement of the track rails during the travel of the rolling stock thereover.

10 The main object of the invention is to provide a simple, novel, durable, economical, practical and efficient rail anchor formed from a single bar or plate of suitable high grade spring steel of the desired dimensions 15 and possessing the required strength, which may be easily and readily applied to the base of a track rail and securely maintained in its proper operative position thereon, and which will always effectively grip and clamp 20 the rail base and co-operate with a stationary part of the railway road bed to prevent the track rail from creeping.

Another object of the invention is to so 25 construct the improved device that it will always maintain the required resiliency and tension and exert an extremely tight grip and effective frictional engagement with the track rail under any and all conditions of service, and the greater the twisting strain 30 to which the anchor may be subjected the more intense gripping action is imparted thereto.

The foregoing and such other objects as 35 may appear from the ensuing description are accomplished by the construction, formation, location and combination of the several parts hereinafter more fully described, illustrated by the accompanying drawings, and particularly pointed out in the claims app- 40 pended hereto, it being understood that slight changes in the precise form, proportions and minor details of the construction may be resorted to without departing from the spirit or sacrificing any of the advan- 45 tages of the invention.

In the accompanying drawings forming a part of the specification it will be seen that:

Figure 1 is a side elevation of the improved device embodying our invention showing a 50 track rail in cross-section and the device at-

tached to the base of said rail showing the position assumed by one of its clamping members before it is caused to clamp the adjacent edge of the rail.

Figure 2 is a central longitudinal section 55 of the anchor device, showing it clamped in operative position to the base of a track rail and showing the track rail in cross-section.

Figure 3 is an enlarged perspective of the device detached from the track rail. 60

Figure 4 is a side elevation showing the blank from which the rail anchor is formed, and showing the first step in the formation of said anchor from the blank. 65

Figure 5 is an end elevation of the blank 70 shown in Fig. 4.

Figure 6 is a side elevation of the anchor showing the second step in the formation, and

Figure 7 is a side elevation showing the 75 third and final step in the complete formation of the improved rail anchoring device.

In the embodiment of the invention as illustrated it will be seen that the numeral 1 designates a railway track rail, and 2 an 75 underlying cross-tie forming a stationary part of the railway road bed and supporting the rail 1, the said rail having a tendency to creep, when subjected to the intense strain caused by the travel of the rolling stock 80 thereover.

This novel and improved rail anchor is formed from any suitable or desirable metal, but is preferably formed from a single bar of high grade spring steel that is rolled with 85 a reinforced portion 3 at each side of the bar where it is about five-eighths of an inch thick, while its central portion from 4 to 4' is reduced to a thickness of about three-eighths of an inch. The said bar is then cut into the desired length such as is shown in Fig. 4, for forming this type of anchor, said Fig. 4 showing that by the first step in forming this particular type of anchor that by a single operation any suitable number of holes are punched through the bar in order to furnish the desired resiliency thereto, and at the same time a portion of the metal is forced outwardly from the bar to form an integral 95 extension 5 forming a rail gripping member 100.

adapted to clamp tightly against one edge of the track rail when the anchor shall have been forced into its operative position on the base of said rail.

The second step in the operation of forming the anchor device is performed by drop forging or stamping the bar with the formation shown in Fig. 6, while the third and last step in its complete formation consists in simply bending over the vertically extended portion into the formation shown in Fig. 7 to form the upper portion of the jaw member 7 which is adapted to overlap and rigidly clamp against the upper inclined face of the base of the track rail when forced into its operative position on the base portion of said track rail.

It will be perceived that when the anchor device is completely formed it consists of a jaw member 5' provided with an upper portion 7 adapted to clamp tightly against the upper inclined face of one side of the rail, and a lower member 7' adapted to firmly contact with the lower face of the rail base, a depending body portion 8, and an upwardly and outwardly curved resilient portion 9, with a centrally outwardly formed extension 5 adapted to firmly grip into contact with the other edge of the rail base when forced into its operative position.

It will be seen that the wide reinforced side portion 3 of the anchor furnishes unusual strength thereto, and prevents breaking of the device while being forced on the rail and at the same time presents a widened bearing surface against the cross-tie all along its face where it is in contact with the tie, hence obviously prevents the tie from being cut, damaged or defaced.

The upper jaw member 7 is formed with a lower face portion 9' having the same incline as the upper face of the rail base so that when forced on the rail it will have a flat gripping contact therewith, as clearly shown in Fig. 2.

The anchor device is first adjusted on the rail base by hand, it is then forced on the rail by striking the outer side of the jaw member 5' with a suitable sledge or hammer until it is caused to assume the position shown in Fig. 1 with the extension 5 resting beneath the base of the rail under a strong upward spring tension, since the upper surface of the outer end of the resilient portion 9 extends slightly above the horizontal plane of the upper surface of the lower jaw member 7', then by a blow of sufficient strength with the sledge or maul at the point 10 the extension 5 will pass the edge of the rail and snap into close and rigid contact therewith and will remain in its secured position until removed by force.

The anchor is formed with a suitable number of holes or openings 11 punched therethrough to provide the desired resiliency, but when desired such holes or openings may be omitted.

It will be readily evident that the rail anchor device formed in the manner hereinbefore described possesses unusual strength and efficiency; that it will prevent cutting and damage to the cross-tie; that it is easily and economically produced, and may be readily applied to and detached from the base of the track rail.

Having thus described our invention what we claim and desire to secure by Letters Patent is:

1. A single piece rail anchor formed with a reinforced thickened portion at each side thereof extending uniformly throughout its entire length, an intermediate thinner portion, a depending body portion, an overlapping clamping jaw formed at one end portion thereof, and an upwardly extended jaw member adjacent the other end portion disposed intermediate its width.

2. A rail anchor for a track rail formed from a single bar of high grade steel having an overlapping jaw at one end, the lower surface of the upper member of said jaw being formed on the same incline as the upper inclined surface of the rail base, a depending portion, a reinforced portion at each side extending uniformly throughout its entire length, an intermediate thinner portion, and an upwardly extended rail clamping member formed adjacent its other end portion and intermediate its width.

3. A rail anchor for a track rail formed from a single bar of metal having an overlapping jaw member at one end thereof, a depending body portion, an upwardly and outwardly disposed curved portion, and a stamped up jaw extension formed near its other end portion and disposed intermediate the width of said anchor.

4. A rail anchor for track rails of the character described, comprising a single bar of high grade steel formed with a reinforced portion at each side extending uniformly throughout its entire length and an intermediate thinner portion, a jaw member at one end thereof adapted to overlap the track rail base, a clamping jaw extension formed intermediate its width disposed adjacent its other end adapted to engage the adjacent edge of the rail base, and a plurality of openings formed through the thinner portion only of said bar.

ARTHUR E. H. BARILLI.
JACOB A. HYLE.
